JUG

Stewart H. Birrell, Sylvania, and Doyle J. Morgan, Toledo,
Ohio, assignors to Owens-Illinois Glass Company,
Toledo, Ohio, a corporation of Ohio

Filed May 18, 1964, Ser. No. 80,030

Term of patent 14 years

(Cl. D58—5)

FIG. 1

FIG. 2

FIG. 3

FIG. 4

The characteristic features of this design reside in the configuration shown in full lines on the drawings.

We claim:

The ornamental design for a jug, substantially as shown and described.
